MATERIAL MOVING MACHINE

George A. Healy, Santa Monica, Calif., assignor
to Vernon G. Mandt, Columbus, Ohio

Application July 16, 1949, Serial No. 105,114

6 Claims. (Cl. 214—111)

1

2

The present invention relates to loading machines, and more particularly to loading machines of the type in which the material to be loaded is first lifted at the front of the machine and then turned and unloaded from the side of the machine.

More particularly, the present invention is directed to a loading machine in the form of a self-propelling vehicle, in which the elevator or load carrier is disposed at the front of the machine, when in loading position, there being a turntable provided for moving the load carrier in a horizontal plane after it is lifted from its loading position whereby the load can be discharged at the side of the vehicle.

In carrying out the present invention, the load carrier is connected with a carriage and this carriage is guided in its vertical movement by track means. The track means is divided into two sections. The lower section is rigidly connected to the frame of the vehicle and the upper section is carried by a turntable. The load is collected while the load carrier is guided by the lower track means and, after the load is collected, it is elevated from the lower track means to the upper track means. Then the upper track means is rotated horizontally in either direction whereby the load can be discharged from either side of the vehicle.

The invention also contemplates utilizing the upper track means as a boom. The upper track means is pivotally mounted at the lower end thereof and can be rotated about a horizontal axis so that the load can be discharged at a distance from the sides or the front of the machine.

The lower section of the guide means is so constructed and arranged so as to provide a pushing section for moving the load carrier forwardly when the vehicle is moved forwardly. The load carrier can be in the form of a shovel and in such use, the forward movement of the vehicle will force the shovel into the material which is to be moved and loaded into, for example, a truck.

The present invention also contemplates utilizing a cable in the elevating mechanism for lifting the carriage and the load carrier. The carriage and the upper track are so constructed and arranged that, when the carriage reaches substantially its uppermost position, it is retained in position by the track and cable and when the cable is released, the load carrier is tilted to discharge the load carried thereby.

With the foregoing objects and advantages, other objects and advantages of the present invention will be apparent from the following description, reference being had to the accompanying drawing wherein a preferred embodiment of the present invention is illustrated.

In the drawings:

Fig. 1 is a perspective view of the loading machine in the loading position;

Fig. 2 is a fragmentary perspective view of the front end of the machine showing the load carrier in its elevated position with the upper track means turned 90 degrees from the loading position;

Fig. 3 is a fragmentary perspective view similar to Fig. 2 but showing the upper track means tilted and the load carrier in dumping position;

Fig. 4 is a fragmentary sectional view taken substantially on line 4—4 of Fig. 1;

Fig. 5 is a fragmentary sectional view taken on substantially line 5—5 of Fig. 2;

Fig. 6 is a fragmentary sectional view taken substantially along line 6—6 of Fig. 3; and

Fig. 7 is a more or less diagrammatic view of the underside of the turntable and the mechanism for actuating the same.

Referring generally to the drawings, the vehicle is in the form of a tractor 20 having a main frame 21 built of heavy material. This frame supports an axle which carries the front wheels 23 and 24. The rear of the frame carries a vertically extending axle which in turn carries the rear wheel 25. The rear wheel 25 can be turned upon its vertical axis by conventional steering mechanism, the steering wheel being indicated at 27. The rear upper part of the frame 21 carries a motor or engine 29 which is used for propelling the tractor and is also used for actuating a hydraulic pump, not shown. The hydraulic pump is utilized for actuating hydraulic motors, to be later described. The mechanism thus far described is standard mechanism now on the market.

The lift or load carrier may be of any type and the machines may be utilized for moving a load from a high level to a low level or from a low level to a high level. The lift 31 is guided by track means in the form of a lower section 32 and an upper section 33. The upper section 33 is carried by a turntable 35 which preferably can be turned 90 degrees in either direction from a position shown in Fig. 1. Thus the load to be moved from a higher or lower level, can also be moved in a horizontal direction. The upper section 33 is in the form of a boom, it being pivotally mounted as at 36 on frame work 37 carried by the turntable 35.

Referring more in detail to the drawings, the lift 31 is in the form of a shovel, the back of which, when in the lowermost position is engaged by the front of the lower track section 32. In the preferred embodiment, the lower track section 32 includes horizontally spaced tracks 39 and 40 which are formed of heavy metal and are secured to the front end of the frame or chassis 21 and reinforced by strips 41. When the vehicle is moved forwardly, the front end of the tracks 39

and 40 will engage the rear of the shovel 31 and force the same forwardly to dig into the material to be removed.

The track sections 39 and 40 are each C-shaped in cross section, forming channels 43, the open ends of the channels confronting one another. These channels receive the rollers 45 and 46 of the carriage 48. The carriage 48 includes two side plates 49 which are triangular in shape. Plates 49 each carry a stub shaft 51 and a stub shaft 52 for the rollers 45 and 46, respectively. Two brackets 53 are carried on the rear side 54 of the bucket type shovel 31 which is hinged by these brackets and pivots 55 to the carriage plates 49. A shaft 56 is fixed to the plates 49 and extends between the same. This shaft 56 carries pulleys 57 and 58, about which are placed cables 59 of the elevating mechanism. The rear side 54 of the shovel 31 carries brackets 61 to which is fastened the ends of the cables 59.

The tracks 39 and 40, at the bottom are inclined inwardly and downwardly whereby, when the carriage is in the lowermost position, the pivot points 55 are brought relatively close to the ground. It will be seen, particularly from Fig. 1, that when the vehicle 20 is moved forwardly, the front end of the track frames 39 and 40 will engage the shovel near the bottom thereof and the depth to which the nose of the shovel is permitted to dig into the ground can be governed by the adjustment of the cables 59. The shovel being pivotally attached to the carriage, follows the vehicle rearwardly when the latter is moved rearwardly. When the section of the cable 59, to the left of the pulley 57, is pulled upwardly, the upper part of rear side 54 of the shovel will be pulled rearwardly to lift the front end of the shovel, and then upon further raising of the cable, the carriage 48 will be lifted, the rollers 45 and 46 following the channels 43 to the track sections 39 and 40.

The boom or upper track section 33 also comprises tracks 63 and 64 forming channels 65. These tracks are formed of the same type of material as tracks 39 and 40. During the loading operation, that is when the shovel is being filled, tracks 63 and 64 should align vertically, respectively, with tracks 39 and 40 so that, as the cable 59 is pulled upwardly, the carriage 48 will move from the lower track section to the upper track section. The upper end of tracks 63 and 64 are closed as at 66 to provide stops for the top rollers 45. When the rollers 45 are in their uppermost position, rollers 46 are opposite rearwardly extending sockets 68 projecting rearwardly from the rearmost side wall of the tracks 63 and 64. Due to the load of the shovel and its contents, the lower rolls 46 will move into the rearwardly extending sockets 68. Then when the cables 59 are released slightly, the forward end of the shovel will tip downwardly to unload the contents of the shovel. After the shovel has been emptied, the cables 59 are again pulled upwardly to such an extent that the brackets 70, secured on the rear side 54 of the shovel, will engage the stub shafts 51 whereby the carriage 48 will pivot about the axis of the pulleys 57 in a counter-clockwise direction pulling the rollers 46 out of the sockets 68. Then when the cables are released, the carriage will drop downwardly in the tracks 63 and 64.

The top of the boom 33 carries brackets 72 which are spanned by a shaft 73. Pulleys 74 are rotatably mounted on shaft 73 for receiving the cables 59. A frame 76 is carried on the rear side

of the turntable 35, as viewed in Fig. 1. The side walls of this frame carry a shaft 77 which supports reels 78, one for each of the cables 59. The shaft 77 is driven preferably by a hydraulic motor 80 through suitable reducing gearing contained within the housing 81. The driving mechanism for the shaft 77 is also carried by the frame 76. The hydraulic motor is connected by flexible tubing so that it can be operated in any of the positions of the turntable 35.

The turntable is actuated preferably hydraulically and to this end there is provided two hydraulic motors in the form of cylinders and rams. A gear 84 is carried on the underside of the turntable which receives a chain 85. One end of the chain is fastened to one of the rams 86 while the other end of the chain 85 is fastened to the other ram 87. By controlling the flow of fluid to the cylinders 88 and 89, one of the rams moves inwardly while the other moves outwardly and, when so doing, rotates the turntable. It will of course be understood that the motors for the turntable are secured to the chassis 21 and are associated with the turntable only through the chain 85 and gear 84. By manipulating conventional valves, the turntable 35 can be moved 90 degrees in either direction from the position shown in Fig. 1.

As previously stated, the upper track section 33 also functions as a boom since the track sections 63 and 64 are pivotally mounted to the bracket frames 37 as at 36. The boom is moved about a horizontal pivot by rams 92 which are associated with hydraulic cylinders 93. The lower end of the cylinders 93 are each carried by a pivot 94 extending upwardly from the turntable 35. The upper ends of the rams 92 are connected by pivots 95 to the rear side of tracks 63 and 64. The cylinders are connected with a pair of flexible tubes for forcing the rams inwardly and outwardly for raising and lowering the boom.

Preferably the turntable and the track section carried thereby are in a position shown in Fig. 1 during the digging or collecting operation by the shovel 31. That is, the carriage 48 is riding within the tracks 39 and 40 and the upper tracks 63 and 64 are aligned respectively with tracks 39 and 40. After the shovel is loaded, the hydraulic motor is actuated to wind the reels 78, causing an upward tipping movement to be imparted to the nose of shovel 31 and thereafter the raising of the carriage 48 and the shovel 31 upwardly, first along tracks 39 and 40 and then tracks 63 and 64. After the carriage is being guided by tracks 63 and 64, the hydraulic rams 86 and 87 can be actuated to turn the boom 33 to the left or right, as desired, and simultaneously, the rams 92 can be actuated to tilt the boom 33. When the carriage reaches its uppermost position and the shovel is over the place where its contents should be dumped, as for example over the truck body which is to convey the material, the hydraulic motor is actuated to slightly release the cables 59 whereby the contents of the shovel 31 will be emptied. The shovel is then again lowered in track sections 63 and 64 as previously explained while if desirable, simultaneously, the boom can be raised to its vertical position and the turntable 35 turns to the position shown in Fig. 1 whereby when the carriage reaches the lower end of the track sections 63 and 64, said track sections will be aligned with track sections 39 and 40.

If desirable, the rear wall 54 of the shovel 31 may carry a roller 97 arranged to roll on the forward side of tracks 39, 40, 63 and 64 while the shovel is being raised and lowered.

By reason of the turntable, the tracks and the other mechanism herein described, the vehicle 29 need be moved, only, in the direction necessary to move the shovel forwardly, that is, in the digging direction. In other words, it is not necessary to manipulate the vehicle to a position in which it can load onto a truck since the turntable and boom can be manipulated so that the shovel 31 is brought over the body of the receiving truck.

While the form of mechanism herein shown and described constitutes a preferred form it is to be understood that other forms may be adopted all falling within the scope of the claims which follow.

I claim:

1. In a loading machine, a frame; a turntable carried by the frame; a load carrier; elevating mechanism carried by the frame and connected with the load carrier for moving the latter vertically; lower vertically extending stationary guide means carried by the frame for guiding the carrier when the latter is in a lowered position; upper vertically extending guide means for the carrier; means pivotally supporting the upper guide means, on the turn-table, for vertical swinging movement; means for imparting vertical swinging movement to the upper guide means, said upper guide means being mounted for horizontal swinging movement with the turn-table to and from alignment with the lower stationary guide means; and means for imparting turning movement to the turn-table.

2. In a loading machine, a vehicle having a frame; a load carrier; an elevating mechanism carried by the frame and connected with the load carrier for moving the latter vertically; lower vertically extending stationary guide means carried by the frame at the front of the vehicle; a carriage for the load carrier guided by the guide means for moving the load carrier when the vehicle is moved and for guiding the load carrier vertically under the control of the elevating mechanism; upper vertically extending guide means for the carriage; means pivotally supporting the upper guide means, on the frame, for vertical swinging movement, said upper guide means being mounted for horizontal swinging movement to and from alignment with the lower stationary guide means; means for imparting vertical swinging movement to the upper guide means; and means for imparting horizontal swinging movement to the upper guide means.

3. In a loading machine, a vehicle having a frame; a load carrier; an elevating mechanism carried by the frame and connected with the load carrier for moving the latter vertically; lower vertically extending stationary guide means carried by the frame at the front of the vehicle; a support for the load carrier carried by the guide means for moving the load carrier when the vehicle is moved and for guiding the load carrier vertically under the control of the elevating mechanism; a vertically extending boom pivotally mounted for vertical swinging movement carried by the frame at the front of the vehicle, said boom providing guide means for the load carrier at the upper part of the vertical movement of the load carrier; means for imparting vertical swinging movement to the boom; and means for swinging the boom to and from the position in which the load carrier is guided by the guide means from one extreme position to the other.

4. In a loading machine, a frame; a lower upright guide rigidly carried by the front of the frame; an upper upright guide movable into and out of alignment with the lower guide; means pivotally supporting the upper guide, on the frame, for vertically swinging movement; means for imparting vertical swinging movement to the upper guide; means for moving the upper guide into and out of alignment with the lower guide; a load carrier adapted to be guided by said guides; an elevating mechanism carried by the frame and connected with the load carrier for moving the load carrier along the guides.

5. In a loading machine, a frame; a load carrier; an elevating mechanism carried by the frame for moving the load carrier vertically; guide means for the load carrier including an upwardly extending track and a carriage guided by the track, the rear of the load carrier being pivotally attached to the carriage, said elevating mechanism including a cable connected with the load carrier in a plane above the pivotal attachment between the load carrier and the carriage; a pulley carried by the carriage below the connection between the cable and load carrier; a pulley carried by the upper part of the track, said cable being guided by the pulleys, said carriage having a track follower at the upper end thereof, said track having a rearwardly extending socket for receiving the follower when the carriage is at substantially its uppermost position for assisting in retaining the carriage in said position when the cable is released for tilting the load carrier to unload the same.

6. In a loading machine, a vehicle having a frame; a pushing section at the front end of the frame; a load carrier adapted to be engaged by the pushing section for moving the load carrier forwardly when the vehicle is moved forwardly; a carriage for the load carrier; an elevating mechanism carried by the frame and connected with the carriage for moving the latter vertically, said pushing section providing vertically extending guide means for guiding the carriage during the lower part of its vertical movements; upper vertically extending guide means for guiding the carriage during the upper part of its vertical movements; means pivotally supporting the upper guide means, on the frame, for vertical swinging movement, said upper guide means being mounted for horizontal swinging movement to and from alignment with the guide means of the pusher section; means for imparting horizontal swinging movement to the upper guide means; and means for imparting vertical swinging movement to the upper guide means and to the carriage when the carriage is guided by the upper guide means.
